UNITED STATES PATENT OFFICE.

MARTIN L. POWELL, OF NEW CASTLE, INDIANA.

DOOR-OPENER.

SPECIFICATION forming part of Letters Patent No. 276,626, dated May 1, 1883.

Application filed January 6, 1883. (No model.)

To all whom it may concern:

Be it known that I, MARTIN L. POWELL, a citizen of the United States, and a resident of New Castle, in the county of Henry and State 5 of Indiana, have invented a new and useful Improvement in Door-Openers, of which the following is a specification, having reference to the accompanying drawings.

The object of my invention is to enable a 10 person approaching a door to open it by the weight of his body; and it consists in the mechanisms for this purpose hereinafter described, and pointed out in the claims.

The accompanying drawings illustrate my 15 invention.

Figure 1 is a side elevation. Fig. 2 is a front elevation.

Like letters indicate the same parts.

The mechanism for opening the door is 20 designed to be mainly concealed in the partition, and, as shown in Fig. 1, is attached to the door-jamb *a*. A bent lever, *b*, having a vertical arm, *c*, standing behind the casing *d* of a door, and a horizontal arm, *e*, which projects through 25 the casing, is fulcrumed at *f* to a plate, *g*, secured to the door-jamb. Secured to the vertical arm of lever *b* is a flat spring, *h*, which engages a notch in a sliding bolt, *i*. Said sliding bolt projects through the casing, and its 30 end rests against the latch *j* of the door. A vertical sliding bar, *k*, is secured to the casing of the door in such a position that its upper end rests against the lower edge of the latch. Bar *k* is connected at its lower end with a 35 short lever, *l*, which has its fulcrum at *m*. The other end of lever *l* is connected to the horizontal arm of lever *b* by rod *n*. A second bent lever, *o*, is also fulcrumed on plate *g*, and is 40 connected with lever *b*, below its fulcrum, by a short rod or link, *p*.

The operation of my device is as follows:

The door being closed, a person approaching it places the foot on the horizontal arm *e* of lever *b*, or on lever *o*, applying the weight of the body thereto, and thus depressing the lever. 45 As the lever is depressed spring *h* is put in tension and sliding bolt *i* is forced against the latch *j*. At the same time vertical bar *k* is forced upward against the latch, and the latch is raised out of the catch-plate *r*, and the door 50 being released is pushed open by the recoil of spring *h*, operating against the latch through sliding bolt *i*. The foot of the person having been removed the levers and sliding bolts are returned to their normal position by a spring, *s*. 55

I claim as my invention—

1. The combination, with a door-latch secured to a door, of a bent lever adapted to be depressed by a person approaching the door, and means, substantially such as described, for 60 causing weight, when applied to said lever, to exert simultaneously an upward and an outward pressure against the latch, substantially as and for the purpose set forth.

2. The combination, with a door-latch secured to a door, of a bent lever adapted to be depressed by a person approaching the door, and means, substantially such as described, for 65 causing weight, when applied to said lever, to exert simultaneously a positive upward pressure and a yielding outward pressure against the latch, substantially as and for the purpose set forth. 70

3. The combination, with a door-latch secured to a door, of sliding bolt *i*, spring *s*, 75 bent lever *b*, spring *h*, vertical bar *k*, lever *m*, and rod *n*, substantially as shown and described, for the purpose specified.

MARTIN L. POWELL.
